C. P. STOCKTON

FASTENER

Filed Nov. 21, 1923

Inventor:
Charles P. Stockton
by L. Hammerer, Atty.

UNITED STATES PATENT OFFICE.

CHARLES P. STOCKTON, OF MELROSE, MASSACHUSETTS, ASSIGNOR OF ONE-HALF TO
GEORGE C. THOMAS, OF MALDEN, MASSACHUSETTS.

FASTENER.

Application filed November 21, 1923. Serial No. 678,616.

To all whom it may concern:

Be it known that I, CHARLES P. STOCKTON, a citizen of the United States, a resident of Melrose, in the county of Middlesex and 5 State of Massachusetts, have invented an Improvement in Fasteners, of which the following is a specification.

This invention relates to that class of fasteners which are primarily designed and 10 intended for use to fasten overshoes, rain-coats and the like, in which two fastener members are connected at opposite ends to the garment portion to be fastened and are adapted to be adjustably connected.

15 The invention has for its objects to provide a form fastener of this type in which all projecting parts are eliminated which are likely to catch on the clothing, also to provide a fastener with which the members 20 are unlikely to become accidentally disengaged and which may be readily manufactured, to a large extent, by a stamping process.

I accomplish these objects in the manner 25 hereinafter described and as illustrated in the accompanying drawing in which:

Fig. 1 is a perspective view of a pair of fastener members embodying my invention, on an enlarged scale.

30 Fig. 2 is a plan view of the under side thereof.

Fig. 3 is a longitudinal section at line 3—3 of Fig. 2.

Fig. 4 is a sectional view at line 4—4 of 35 Fig. 3.

Figs. 5 and 6 are sectional views at lines 5—5 and 6—6, respectively, of Fig. 2.

According to my invention, I provide a pair of oblong shaped fastener members 40 *a* and *b*, which are adapted to be attached at opposite ends, respectively, to the opposite portions of an overshoe or garment to be fastened together, one on the other, the outer member *a* having its longitudinal edge portions bent downward and inward to form guideways *c* for the edge portion of the inner member *b*, so that the latter may slide freely therein. The members may be curved as shown, or straight, according to the purpose for which they are to be used. The 45 inner member *b* is slotted from its end opposite the end which is attached along its middle portion, forming a slot *d*, and a series of corresponding, segmental shaped recesses 50 *e* are formed in the opposite side portions of

said slot, forming intermediate projections *f*, which are directly opposite each other, the distance between the ends of the opposite projections corresponding to the width of the slot. The opposite recesses may be considered as circular holes of uniform diameter and intersected diametrically by the longitudinal slot *d*.

A spring tongue *g* is struck out from the metal of the member *a*, at the middle thereof, 65 and in a position in which it extends longitudinally of the member from its attached end, and is spring set in a position in which it extends divergently from the outer surface of the member, so that the tip or end portion *g'* of the tongue is normally held at a substantial distance from said outer surface. The end portion *g'* is slightly enlarged and has rounded edges tapering to the extreme end and a stud *h* is fixed at one end in the 70 middle of said end portion *g'* said stud having a flange portion *i*, at its opposite end, the diameter of which is somewhat greater than the diametrical distance from the bottom of one recess *e* to the bottom of the opposite recess, a head-portion *j*, the diameter of which is approximately the same as the circular holes forming said recesses, so that it may be received thereby, and an intermediate shank portion *k*, the diameter of 75 which is slightly less than the distance between the opposite projections *f*. The end portion of the stud which is fixed in the tongue, is preferably secured by riveting, as indicated in Fig. 3. The tapering end portion of the tip portion *g'* of the tongue is 80 bent downward at approximately right angles, to form a guard lug *m*, which depends therefrom to a point slightly below the level of the outer surface of the member *a*, so 85 that in the normal position of the tongue, shown in Fig. 3, there will be no projecting end which is likely to catch on the clothing. A pair of longitudinal ribs *n* are struck up 90 in the inner member *b* to give it increased 95 stiffness.

When the fastener members are to be connected, the tongue *g* is depressed to its fullest extent, causing the shank portion *k* of the stud to be moved into a position 100 opposite the guideways *c*, so that when the member *b* is inserted in the guideways, the slot *d* will receive this portion of the stud, and as the distance between the ends of the projections *f*, or the narrowest portions of 110

the slot is slightly more than the diameter of the shank portion *k*, the member *b* may be slid beneath the member *a* to any point desired, until the inner end of the slot engages the stud. If it is desired to lock the members together at this or intermediate points, the tongue is simply released and its resiliency draws the stud outward, so that its head portion *j* enters one of the pairs of recesses *e*, as shown in Figs. 3 and 5. In this position the sides of the stud will engage the sides of the recesses, or the projections and lock the member *b* against sliding movement beneath the member *a*.
10 To disengage the members it is merely necessary to press the tongue inward until the head portion *j* is disengaged from the recesses in the slot of the inner member and then the members may be slid relatively as will be obvious.
15

In the locked position the parts will be securely held and the probability that the tongue will be accidentally pressed inwardly to a sufficient extent to cause them to become
20 unlocked is remote.

The two fastener members are of such a construction that they may be readily stamped out of sheet metal and the stud may be readily made by automatic
25 machines.

I claim:

1. A fastener comprising an outer and an inner member adapted for attachment at opposite ends, said inner member being arranged for slidable connection with the outer member at its inner side and having a longitudinal slot therein extending from its unattached end, said slot having a series of oppositely disposed recesses opening thereto at each side, a resilient tongue connected to said outer member at its attached end and normally extending towards its opposite end in divergent relation with the outer side thereof, a locking projection rigid with said tongue and extending from the end thereof through the outer member in position to enter the slot of said inner member, said projection having an intermediate shank portion adapted to be received by said slot and a head portion at its inner end adapted to be engaged in the recesses thereof when the tongue is in normal position to be disengaged therefrom when it is pressed inward.
2. A fastener comprising oblong outer and inner members, arranged for attachment at their opposite ends, the outer member having longitudinal guideways in which the inner member is arranged to slide at the inner side thereof, and said inner member having a longitudinal slot extending from its free end, said slot having a series of oppositely disposed recesses opening thereto, a resilient tongue connection to the outer member adjacent its at-

tached end and extending at the outer side thereof towards its opposite end in divergent relation thereto, said tongue having a locking stud fixed therein at its end and movable thereby through said members, said stud having an intermediate shank portion adapted to be received by said slot, a head portion at its inner end adapted to be received by said opposite recesses to lock the members against relative sliding movement and a flange at the inner end of the head to engage the inner side of the inner member, said stud being movable by said tongue between positions in which either its intermediate portion or its head portion may be held in the slot.
75

3. A fastener comprising an outer and an inner member adapted for attachment at opposite ends, said inner member being arranged for slidable connection with the outer member at its inner side and having in its middle portion a series of circular holes which are connected by a longitudinal slot extending from its unattached end, a resilient tongue connected to and extending longitudinally of said outer member and spring set in divergent relation relative thereto, and a stud fixed in the end of said tongue and extending through said outer member into the slot of the inner member,
80

said stud having a circular head portion at its inner end adapted to be received by said circular holes and an intermediate shank portion adapted to be received by said slot, the length of said portions corresponding to the thickness of said inner member whereby either portion may be held in said slot.
95

4. A fastener comprising an outer and an inner member adapted for attachment at opposite ends, said inner member being arranged for slidable connection with the outer member at its inner side and having a longitudinal slot therein extending from its unattached end, said slot having a series of
100

recesses opening thereto at one side, a resilient tongue connected to said outer member at its attached end and normally extending towards its opposite end in divergent relation with the outer side thereof, a locking projection rigid with said tongue and ex-
105

tending from the end thereof through the outer member in position to enter the slot of said inner member, said projection having an intermediate shank portion adapted to be received by said slot and a head portion at its inner end adapted to be engaged in the recesses thereof when the tongue is in normal position to be disengaged therefrom when it is pressed inward.

5. A fastener comprising an outer and an inner member adapted for attachment at opposite ends, said inner member being arranged for slidable connection with the outer member at its inner side and having a longitudinal slot therein extending from its
110

120

130

unattached end, said slot having a series of recesses opening thereto at one side, a resilient tongue connected to said outer member at its attached end and normally extending towards its opposite end in divergent relation with the outer side thereof, a locking projection rigid with said tongue and extending from the end thereof through the outer member in position to enter the slot of 5 said inner member, said projection having an intermediate shank portion adapted to be received by said slot and a transversely

projecting head portion at its inner end having a locking portion adapted to enter any one of said recesses when the tongue is in 15 normal position, and a stop portion arranged to engage the inner side of the inner member to limit the outward swinging movement of said tongue when said locking portion is engaged in one of said recesses. 20

In testimony whereof, I have signed my name to this specification.

CHARLES P. STOCKTON.
